DOUBLE TROLLEY TURNOUT

Warren J. Lewis, Mansfield, Ohio, assignor to The Ohio Brass Company, Mansfield, Ohio, a corporation of New Jersey

Application August 9, 1950, Serial No. 178,474

7 Claims. (Cl. 191—38)

1

This invention relates to an overhead trolley system and has particular use in mines in which twin trolley wires are used.

The invention has particular reference to a switching point at which a portion of the main trolley wires are biased from a main line position to a branch position.

In case of a single trolley wire system, it is merely a matter of placing a frog at the point of branching, as there is no relative movement of the main and branch wires, but there is no practical frog to cover the situation where a pair of overhead wires of opposite polarity are in use.

The herein described construction covers means for switching a portion of the main trolley wires from a straight through or main position to a branch position and vice versa, and at the same time avoid the possibility of interference between the wires of opposite polarity as would normally be the case with the wires positioned in a common plane of movement or horizontal plane.

In the drawing—

Fig. 1 shows a top plan view of a pair of main and branch wires in the same or common plane together with supports for attaching the parts to a mine roof and also shows means for yieldingly holding the wires in their adjusted relation.

Fig. 2 is a side view of Fig. 1 showing the wires and supports as attached to a mine roof which is shown in section.

Fig. 3 is a section on the line 3—3 of Fig. 1 showing the movable pair of trolley wires as shifted to their branch position as in Fig. 1 and showing various parts as supported from a mine roof also shown in Fig. 2.

Fig. 4 is a section on the line 3—3 of Fig. 1 showing the movable pair of trolley wires as shifted to the main line position as shown by dotted lines in Fig. 1 and also showing parts as supported by a roof as in Fig. 2.

Fig. 5 shows a section on the line 3—3 of Fig. 1 with the movable or switch wires in mid position and in particular the out-of-alignment relation of the main and branch wires with regard to the movable or switch wires in passing from one extreme position (Fig. 3) to the other extreme position (Fig. 4) and vice versa.

In the system disclosed, the main or through wires are *a* and *b* and *a'* and *b'* while the branch wires are *c* and *d*. The main wires are provided with insulated supports 1, 2, 3 and 4 and the branch wires are supported by insulators 5 and 6.

The supports 1 and 2 are secured to their respective wires to anchor same and rigidly attached to the mine roof 7 so as to hold the wires stationary at the point where the switch wires

2

x and *y* find their lateral movement which is at a distance from their free ends.

The main wires *a'* and *b'* are provided with the rigid supports 3 and 4 which anchor the same and are secured to the respective wires at or adjacent their free ends and these insulator supports are fixed to the mine roof and hold the wires *a'* and *b'* stationary. The same is true of insulators 5 and 6 associated with trolley wires *c* and *d*.

It is important that the wires *a'*, *b'*, *c* and *d* are held in fixed and properly spaced alignment.

The switch wires *x* and *y* which are a continuation of wires *a* and *b* extend to the fixed ends of the wires *a'*, *b'*, *c* and *d* and almost contact the same.

The switch wires *x* and *y* are bendable being of hard-drawn copper or bronze and the free ends may be swung into alignment with the ends 20 of wires *a'* and *b'* or with *c* and *d*, but support means is provided for the free ends during such swinging operation.

The support means for the free ends of the switch wires *x* and *y* consists of a rail 8 with straight and aligned ends 9 and 10 which are connected by a depressed concaved portion 11. This support means which is hereinafter called a yoke, extends over the top of the switch wires for their full extent at least of their lateral movement and in spaced relation to the switch wires and each end of the yoke is provided with a support 12 with means 13 to secure it to the mine roof.

Mounted upon the yoke is a transversely movable slide or support 14 for the free ends of the switch wires and which is mounted upon the yoke and may be fitted with rollers or wheels 15 for easier movement. The slide is provided with insulating support 16—17 secured to the switch wires at their free ends to hold the wires in fixed and spaced relation and to move the wires as the slide is moved from side to side. The yoke is provided with stop pins 18 at each end to limit the movement of the slide when the switch wires align with the main and branch wires.

The installation includes a pair of spaced upright posts 19 extending between the roof of the mine floor on each side of the yoke and to each post is secured a pulley 20 over which pass the ropes 21—22 attached to their respective ends of the slide 14 whereby the slide and switch wires may be moved from one extreme position to the other extreme position. Other means, such as electric, air or hydraulic may be used to operate the switch wires and could be attached at H.

In order to yieldingly maintain the slide and

switch wires in their adjusted positions a support 23 is provided to be secured to the mine roof at a point removed from the ends of the switch wires. There is also provided a support 24 to be secured to the mine roof at a point intermediate the supports 4 and 5 and the support 23.

Secured to the center of support 23 and to the slide 14 is an extension type spring 25, and secured to the center of the support 24 and to the slide 14 at a point adjacent to that of spring 25 is a compression type spring 26 also known as an over-center spring which holds the slide in either its main or its branch position. The spring 26 is provided with a telescopic type core to keep it aligned.

The mine roof is cut out at 27 and 28 to accommodate the several parts of the device as shown in Fig. 2.

In the operation of the device, if the switch wires are at the branch position (Fig. 1), the operator will pull on the rope 24 which will move the slide from the position in Fig. 3 to that in Fig. 4 and the switch wires will take the position shown by the dotted lines in Fig. 1. The over-center compression spring 26 and the tension spring 25 will assume the positions shown by dotted lines in Fig. 1 and hold the slide against the stop 18.

The yieldable holding means may consist of the over-center compression spring 26 alone, but this will force the slide 14 against the yoke 8 with considerable force creating considerable friction between the slide and yoke, however the over-center tension spring 25 will relieve this pressure and the two springs acting together will result in a resultant acting more nearly in line with the direction of movement of the slide 8 having decreased the direct pressure upon the yoke.

In passing from the position shown in Fig. 3 to that shown in Fig. 4, the slide will follow the upper edge of the yoke due to the member 15 positioned above and below the track 8 and before any switch wire of one polarity is in alignment with a branch or main wire of the opposite polarity the slide will have followed along the portion 11 of the yoke and thus the ends of the switch wires will have passed from the branch to the main wires underneath the same, as shown in Fig. 5.

If the switch wires moved laterally in the same plane as the trolley wires, a short circuit would probably result between the positive wire *x* and the negative *b'* and also between the negative wire *y* and the positive branch wire *c*, since the free ends of the wires practically contact when in alignment.

There are modifications which will occur to those skilled in the art, but which will fall within the scope of this invention, for instance other shifting means may be substituted for the ropes 24-22 and for holding the slide in either position or the trolley wires *d*-*y*-*b'* may be in a parallel and the wires *c*-*x*-*a'* may be in a parallel plane below the first plane in which case the dip 11 in the yoke may be made straight. What I desire to secure by Letters Patent is set forth in the foregoing claims.

I claim:

1. In combination; a pair of main trolley wires of opposite polarity having a fixed portion and a laterally movable portion and a pair of fixed branch wires of opposite polarity, the branch wires spaced from the fixed portion of the main

wires, the movable portion of the main wires being bendable at a point remote from their free ends until the free ends are in alignment with the free ends of either the free ends of the fixed portion of the main wires or the free ends of the fixed branch wires, all wires being normally in a common plane, insulating supports at the free ends of the branch wires and of the said fixed portion and at the said remote point of the main wires to support the said movable portion at the remote point, an insulating slide attached to the free ends of the switch wires whereby the free ends are held in spaced relation, a yoke shaped track with secured ends to support the said slide and upon which the slide may be moved to either of its two positions to bring the free ends of the switch wires into longitudinal alignment with the free ends of the branch and of the fixed main wires, the end portions of the track being straight and aligned with each other to support the slide in its aligned positions, the portion of the track intermediate the end portions of the track being depressed to permit the slide to dip down whereby the ends of the switch wires secured thereto will pass laterally below the free ends of the said fixed wires and branch wires in passing from one position to the other, and spring means to yieldingly hold the slide in either of its extreme positions, the said spring means comprising a compression spring, and a tension spring acting counter to the compression spring both as to its holding resultant and its pressure of the slide against the yoke-shaped track.

2. In combination, a pair of spaced trolley wires of opposite polarity, a second pair of spaced trolley wires of opposite polarity spaced from the first pair, a third pair of spaced trolley wires of opposite polarity, means to support the free ends of the first and second pair of trolley wires to hold them in fixed and insulated relation, means remote from the free ends of the said third pair of trolley wires to support, insulate, guide and move the free ends of the said third pair of trolley wires to either of two positions, one position in longitudinal alignment with the first pair of wires and the other position in longitudinal alignment with the second pair of wires, the last said means including a yoke shaped track and a slide, the said track supporting and guiding the slide and having concaved means to depress the slide and the third pair of trolley wires as the wires are moved from one position to the other to prevent interference between any two wires of opposite polarity, the slide provided with guide means which rotate as the slide moves along the track, manually operable means secured to the slide to move the slide into and out of the depressed portion of the track and to either of its positions and a pair of cooperating springs to yieldingly hold the slide and the third pair of trolley wires in either of their two aligned positions and to void the friction between the slide and track due to the pressure of one of the springs upon the slide.

3. A switching system which includes a pair of spaced and fixed trolley wires and a second pair of trolley wires spaced from the first pair of wires, means to support the free ends of the said pairs of trolley wires and hold their free

ends in fixed and insulated relation in a common plane, the wires of each pair being of opposite polarity, a third pair of spaced trolley wires of opposite polarity bendable into longitudinal alignment with the wires of the first and second pair of trolley wires, the free ends of the third pair of trolley wires being spaced from the free ends of the trolley wires with which they are aligned, means to support the third pair of trolley wires at a point remote from their free ends whereby the portion of the third pair of wires between the support and their free ends is movable into alignment with either one or the other of the first two said pair of trolley wires, transversely movable support means for the free ends of the third pair of trolley wires and to move the same to either of said aligned positions and to move the last said free ends out of the said common plane as they are moved from one of said positions to the other, and an over-center spring means to yieldingly maintain the third pair of trolley wires in either position, the said spring means including a compression type spring and a tension type spring cooperating with the compression type spring to relieve the direct pressure upon the support means created by the compression spring without eliminating the resultant force of the compression spring along the line of the direction of movement of the free ends of the third pair of trolley wires and to yieldingly hold the said free ends in either of their aligned positions.

4. A switching system comprising three pair of trolley wires, the wires of each pair spaced from each other and of opposite polarity and each pair of wires spaced from the other pair, the said three pair of wires being so arranged that the wires of one pair may be aligned with those of either of the other two pair, the wires of said one pair being universally bendable at a point remote from their free ends whereby the said one pair of trolley wires may be longitudinally aligned with either of the other pair of wires, a slide and fixed support therefor for supporting the free ends of the said one pair of trolley wires and manually controlled means for actuating the slide, means associated with the slide to yieldingly hold the slide with the attached ends of the said one pair of wires in alignment with the free ends of either of the other two pairs of wires, the said means comprising an over-center compression type of spring providing a resultant force acting along the fixed support to hold the slide in either end position and creating friction between the slide and fixed support due to pressure of the compression spring upon the slide, and a tension type of spring acting upon the slide in opposition to the pressure created by the compression spring to reduce the friction between the slide and fixed support, whereby the force opposing the movement of the slide from one position to the other as a result of said friction is materially reduced without completely reducing the holding force of the spring.

5. In a support for a trolley system using a pair of trolley wires of opposite polarity and a pair of branch wires at a switching point, the combination of an elongated yoke shaped track having its ends secured in fixed position, the track provided with straight and horizontally aligned and spaced portions and a central depressed portion; a guide and support means for the free ends of a pair of spaced and laterally movable trolley wires of opposite polarity, the guide and

support provided with insulating means to receive the free ends of the trolley wires, the guide and support means also provided with freely rotatable means mounted on the track whereby the 5 guide and support means may be freely moved from end to end of the track and be depressed and then raised as it moves along the central portion of the track; means to provide a resultant force acting in the direction of movement of the 10 guide and support means to yieldingly hold the guide and support means at rest upon the straight portion at either end of the yoke shaped track, the said means comprising an over-center spring under compression having one end secured to the 15 guide and support means and the other end secured to a fixed support at a point spaced from the guide and support means and midway between the positions of rest of the guide and support means and a second spring under tension 20 secured to the guide and support means adjacent the end of the first said spring and the other end secured to a fixed support at a point spaced from the fixed support of the first said spring whereby the pressure of the first said spring 25 against the guide and support means is reduced by the tension in the second spring.

6. An electric installation for a transportation system in a tunnellike passage or excavation comprising, a roof member, a pair of spaced and 30 fixed trolley wires and a second pair of trolley wires spaced from the first pair of wires, insulating means to secure the free ends of the said pairs of trolley wires directly to the roof member and hold their free ends in fixed and 35 insulated relation to each other and to the roof member and also in a common plane, the wires of each pair being of opposite polarity, a third pair of spaced trolley wires of opposite polarity bendable at a point remote from their free ends 40 into longitudinal alignment with the wires of the first and second pair of trolley wires, the free ends of the third pair of trolley wires being spaced from the free ends of the trolley wires with which they are aligned, insulating means 45 to secure the third pair of trolley wires directly to the roof member at the point of movement whereby the portion of the third pair of wires between the last said means and their free ends is movable into alignment with either one or the 50 other of the first two said pair of trolley wires, the said portion of the third pair of trolley wires forming switch wires to guide current collectors on a passing locomotive onto either one or the other of the first or the second said pair of trolley 55 wires, support means for the free ends of the switch wires and to move the free ends thereof into longitudinal alignment with either of the other two pair of trolley wires and to move the free ends of the switch wires out of the said 60 common plane of the first two pair of trolley wires as the switch wires move from one of said positions to the other, the said support means comprising a laterally disposed elongated track member having its ends secured directly to the 65 roof member and provided with relatively short horizontally aligned straight end portions connected by a concaved central portion arranged to dip downward, a carriage mounted on the track member and depending therefrom and movable 70 from end to end of the track member, stop means on the said straight end portions adjacent their union with the ends of the concave portion whereby the carriage will be immediately guided downward in passing from either end of the track

member to the other end thereof, the carriage provided with insulating means to receive and secure the free ends of the switch wires to the carriage in insulated relation thereto and to each other, the roof member provided with a hollowed out portion above the support means sufficiently large to receive the said track member with the lower portion of the carriage projecting below the normal line of the roof member and the switch wires in longitudinal alignment with the other two pairs of trolley wires, and spring means secured to the carriage and anchored to the roof member at a point removed from the said support means to yieldingly hold the carriage in either of its aligned positions with the other two pair of trolley wires, other spring means acting counter to the pressure of the first said spring means in a direction normal to the track member and also acting counter to the pressure of the first said spring means in the direction of movement of the carriage but without completely nullifying the pressure of the first said spring in yieldingly holding the carriage at either end of the track and means secured to the carriage means to actuate the support to either of its two positions.

7. A support for a pair of movable trolley wires and provided with means attachable to the wires at or adjacent to their free ends to move the wires to either of two lateral positions, the support comprising an elongated supporting and guiding track having means at the ends to attach the member to an overhead support, a portion of the opposite ends of the said member being straight and aligned, and a portion intermediate

5
10
15
20

the ends formed with a concave depression with respect to the end portions, a slide movably mounted on the supporting and guiding member, and provided with means engaging the opposite edges of the track in rotatable relation thereto to cause the slide to follow the said ends and depressed intermediate portion of the track, a pair of springs attached at one end to the slide to yieldingly hold the slide in either of its lateral positions, means to support the other end of each spring to hold it fixed, one spring exerting a compression force upon the slide and thereby creating friction between the slide and track, and the other spring exerting a tension force upon the slide to greatly reduce the friction, and the two springs cooperating to maintain a resultant force acting along the direction of travel of the slide, and insulating means associated with the slide, and having means attachable to the free ends of the trolley wires.
